APPLIQUÉ ATTACHMENT FOR SEWING MACHINES

Harry R. Prall, Upper Darby, Pa.; Swarthmore National Bank and Trust Company, administrator of said Harry R. Prall, deceased, assignor to B. L. Braun

Application August 3, 1944, Serial No. 547,845

2 Claims. (Cl. 112—139)

This invention relates to appliquéd attachments for sewing machines such as are employed in applying appliquéd to fabrics.

A conventional sewing machine ordinarily includes a presser bar that carries a presser foot. During sewing operations the work is held between this presser foot and the bed of the machine. The presser bar is raised or lowered to cause a corresponding movement on the part of the foot when it becomes necessary to make a change in the work.

When a sewing machine is used for the purpose of applying appliquéd, such as braid or embroidery, to fabrics, it has been the practice to employ a presser foot that includes an opening through which the appliquéd passes. The needle of the machine during stitching operations passes through this opening and centrally thereof. Theoretically, the needle is intended to pierce the center of the appliquéd. However, due to the fact that in many instances there is a discrepancy between the size of the opening and the appliquéd, a shifting of the latter is possible which causes the needle to pierce the appliquéd at a point removed from the center thereof.

Furthermore, from the very nature of the type of work being done it is necessary that the appliquéd be attached along lines including curves and bends and when such lines are accommodated there is an inevitable tendency for the appliquéd to assume difficult angular positions with respect to the opening in the presser foot. The same undesirable result is forthcoming in that the needle will not pierce the exact center of the appliquéd under these conditions.

Certain attempts have been made to partially remedy this condition, such as providing presser feet with openings of different sizes, each sized opening being intended to accommodate a corresponding size of appliquéd. It is obvious that such an arrangement calls for frequent changes in the presser foot of the machine, with the accompanying loss of time.

Attempts have also been made to guide the appliquéd and maintain a constant angular relation with respect to the opening in the presser foot. However, these have not been entirely satisfactory, particularly in the difficulties presented in threading the appliquéd through the opening in the presser foot, and further, because the guiding functions have not been properly carried out.

With the foregoing conditions in mind, this invention has in view, as its foremost objective, the provision of an appliquéd attachment for sew-

ing machines which includes a presser foot of novel construction and with which is associated guiding means for accurately controlling the appliquéd with respect to the opening in the presser foot.

More in detail, the invention has in mind an arrangement in which the presser foot is formed with an opening which is variable in size. In carrying out this idea, the opening takes an elongated form and communicating therewith is a slot at one side through which the appliquéd work may be passed, thus eliminating the need for the threading operations. A guide plate is slidably carried by the presser foot and is movable to close the slot at the side and vary the size of the opening in the presser foot so that the latter will accurately conform to the size of the appliquéd.

Another important object of the invention is the provision of a presser foot which carries at one side an angularly disposed flange which is formed with the elongated opening and slot aforesaid. This inclined flange also carries the guide plate. With this side flange so angularly disposed the effective end of the opening in which the appliquéd is positioned is located at the joinder of the flat bottom of the presser foot and the inclined side flange. Thus, the operator is enabled to accurately follow the lines which the appliquéd is intended to take.

Another important object of the invention is the provision of novel means for guiding the appliquéd with respect to the opening in the presser foot.

In accordance with this objective of the invention, a piece of metal is struck from the flange at the side to provide a loop having an entrance at the same side as the slot. Thus, the appliquéd may be inserted into this loop at the same time that it is passed through the slot in the side flange of the presser foot. The guide plate carries an upturned flange that is formed with a notch in alignment with this loop and the elongated opening in the presser foot. During actual sewing operations, the appliquéd will pass through the notch in the flange of the guide plate and be maintained in this notch by the loop. The braid passes beneath the loop and through the opening in the presser foot.

Various other more detailed objects and advantages of the invention will in part become apparent and in part be hereinafter stated as the description of the invention proceeds.

The invention, therefore, comprises an appliquéd attachment for sewing machines consist-

ing of a presser foot having an inwardly inclined flange at one side. An elongated opening is formed in this flange and the opening terminates at the joinder of the flange and the flat bottom of the presser foot. A slot extends from the side of the flange into this opening. A guide plate is slidably carried by this flange and an upturned flange on the guide plate is formed with a notch. A strip of metal is integrally joined to the inclined flange of the presser foot and formed with a loop in alignment with the notch in the guide plate and the elongated opening.

For a full and more complete understanding of the invention, reference may be had to the following description and accompanying drawing, wherein:

Figure 1 is a perspective view from the side of the parts of a sewing machine with which this invention is concerned,

Figure 2 is a detailed perspective of the presser foot per se, while

Figure 3 is a detail perspective of the guide plate that is carried by the presser foot, and

Figure 4 is a top plan view of the presser foot and guide foot in assembled relation.

Referring now to the drawing, wherein like reference characters denote corresponding parts, and first more particularly to Figure 1, the presser bar of a sewing machine is depicted at 10. This presser bar is raised or lowered by the actuating lever shown at 11, the operating connections between the lever 11 and bar 10 being well-known in this art and not herein illustrated. The lower portion of the presser bar 10 is flattened out, as shown at 12, and a set screw, represented at 13, is threaded into a screw opening in the lower portion 12 of the presser bar. The appliquéd attachment of this invention comprises a presser foot which is referred to in its entirety by the reference character F, and a guide piece G which is carried thereby. The presser foot F includes a channel structure designated C and which channel structure is made up of side flanges 14 and 15 and a bottom 16. The channel C is intended to receive the lower portion 12 of the presser bar 10 and in order for this relation to be established, it is necessary that the set screw 13 be accommodated. Accordingly, a slot 17 is formed in the side 14 and bottom 16. It is obvious that the set screw 13 may be tightened to securely clamp the channel structure C on the lower portion 12 of the presser bar 10.

Integrally connected with the side flange 15 is a flat bottom 18 that is designed to engage the work which may rest on the bed of the sewing machine. Integrally connected to the flat bottom 18, and extending in an upwardly inclined direction from the side thereof, is an inclined flange 19, the line of joinder between the bottom 18 and flange 19 being depicted at 20.

An elongated opening 21 is formed in the side flange 19 and this opening is continued down a slight distance into the bottom 18 beyond the line 20. A slot 22 extends from a free edge of the side flange 19 into the opening 21 and communication with this opening is thus established so that a piece of appliquéd may be passed into the opening 21.

At the side edges of the inclined flange 19 are downturned ears 23, the end portions of which are spaced from the flange 19 to provide guideways designated 24 which receive the free edges of the guide plate G, in a manner to be herein-after pointed out. A strip of metal 25 is defined

by the formation of a slot 26 that extends into the flange 19 from the same free edge that is formed with the slot 22, this strip 25 being integrally joined to the inclined flange 19, as represented at 27. The strip 25 is deformed to provide a loop 28 that is substantially in alignment with the elongated opening 21.

Referring now more particularly to Figure 3, the guide plate G is shown as comprising a main guide portion 29 and an upturned flange 30 that is integrally joined thereto by a bend represented at 31. The main body portion 29 is intended to slidably engage the underface of the inclined flange 19 with the free edges of the part 29 snugly received in channels 24. The upturned flange 30 is formed with a V-shaped notch 32 that is substantially in alignment with the loop 28 and opening 21.

It is evident that abutment of the flange 30 with the end of side flange 19 limits movement in one direction of the guide G with respect to the foot F.

While the manner of usage of the above-described attachment is believed to be obvious, it may be briefly described by noting that prior to insertion of the appliquéd, the guide G is withdrawn sufficiently far to leave the slot 22 open. The appliquéd is then passed through the slot into the opening 21. At the same time it is passed through the slot 26 and beneath the strip 25 into the loop 28. With such an arrangement the appliquéd work will naturally fall into the notch 32 wherein it will be maintained by the loop 28 as the latter inhibits upward movement of the appliquéd. The guide plate G is now moved into the channels 24 to close the slot 22 and restrict the opening 21 so that the latter accurately conforms to the size of the appliquéd.

The needle of the sewing machine is represented at N in Figure 1 and is always arranged to pierce the opening 21 centrally thereof and closely adjacent the joinder line 20. At the point where the appliquéd passes through the opening 21 there will always be a fixed angular relation, due to the guiding effects of notch 32 and the fact that the appliquéd is maintained in such notch by loop 28. With the flange 19 inclined upwardly, the operator is enabled to accurately perceive just where the needle end will pierce the work so that the latter may be exactly carried out.

While a preferred specific embodiment of the invention is hereinbefore set forth, it is to be clearly understood that the invention is not to be limited to the exact constructions illustrated and described, because various modifications of these details may be provided in putting the invention into practice, within the purview of the appended claims.

What is claimed is:

1. An appliquéd attachment for sewing machines comprising a presser foot, means for attaching said presser foot to the presser bar of a sewing machine, said presser foot being formed with an opening adapted to receive a strip of appliquéd, a guide plate slidably mounted on said presser foot and formed with an upturned flange carrying a notch adapted to receive said strip of appliquéd, and a strip of metal struck from said presser foot and formed with a loop that overhangs said strip of appliquéd to maintain the latter in said notch.
2. An appliquéd attachment for sewing machines comprising a presser foot including a flat

bottom and an inclined side flange, said flange being formed with an elongated opening that extends at one end into said flat bottom, said flange also being formed with a slot establishing communication between a side edge of said flange and said elongated opening, a guide plate slidably mounted on the underface of said flange and movable into a position closing said slot, said guide plate being formed with a notch adapted

to receive a strip of appliqué, said flange being formed with another slot extending inwardly from the same edge as that carrying said first-mentioned slot to define a strip integrally joined to said flange and which strip is formed with a loop substantially in alignment with said opening and notch.
